CAN WAGON

William L. Shepheard, Norfolk, Va.

Application October 30, 1956, Serial No. 43,595

Term of patent 14 years

(Cl. D14—3)

The sole figure is a perspective view of the right-hand side of a can wagon embodying my new design.

The cans shown in broken lines are for purposes of illustration only.

I claim:

The ornamental design for a can wagon, as shown and described.
